No. 783,883.

PATENTED FEB. 28, 1905.

B. MUMBY.

SAD IRON.

APPLICATION FILED NOV. 16, 1903.

UNITED STATES PATENT OFFICE.

BELLE MUMBY, OF MANCHESTER, IOWA.

SAD-IRON.

SPECIFICATION forming part of Letters Patent No. 783,883, dated February 28, 1905.

Application filed November 18, 1903. Serial No. 181,387.

To all whom it may concern:

Be it known that I, BELLE MUMBY, a citizen of the United States, residing at Manchester, in the county of Delaware and State of Iowa, have invented certain new and useful Improvements in Sad-Irons, of which the following is a specification, reference being had therein to the accompanying drawings.

This invention relates to sad-irons, and particularly to those provided with a detachable handle and designed for use in pressing seams and for other purposes where a narrow ironing-surface is desirable.

One object of the invention is to provide efficient means whereby the handle can readily be connected to and detached from the base part of the sad-iron.

A catch of novel design is used for holding the handle portion in place on the base, and said catch is disposed in such manner that it will not prematurely release the handle nor be liable to injury. Further, that part of the handle-section which engages the base is so formed as to facilitate its connection to the base.

The construction also contemplates the provision of a handle-grip of a construction which will add to its strength and durability.

The iron, further, is formed in a novel manner, so as to make it readily adaptable for pressing seams and for use generally where a narrow surface only is desired to be pressed. A long narrow iron with narrow pressing-surface is provided for this purpose, and the iron may be made of different lengths and of different weights.

An embodiment of the invention possessing all of the foregoing desirable characteristics is delineated for purposes of illustration in the accompanying drawings, forming part hereof, and upon inspection of which novel details in the construction and arrangement of the various parts of the invention will be apparent.

In the drawings like reference characters refer to corresponding parts in the several views, of which—

Figure 1 is a perspective view of the handle-section. Fig. 2 is a bottom view of the handle-section. Fig. 3 is a top view of the

base-section. Fig. 4 is a bottom view of the base-section. Fig. 5 is a view on the line zz , Figs. 1 and 3. Fig. 6 is a view on the line yy , Figs. 1 and 3.

Referring more particularly to the drawings, 1 designates the base of the iron, made long and narrow and the bottom or ironing-surface 2 being made more narrow than the upper part of the base by the sides converging toward the bottom at 3. The toe 4 is made pointed, so as to facilitate guiding the iron. The narrow construction of the base of the iron is to provide a device especially suited for use in pressing seams and for other purposes where it is desired to smooth only a narrow part of the goods being operated upon. A longitudinally-disposed groove 5 is formed in the top part of the iron. This groove has undercut inclining sides 6 and extends from near the toe 4 of the base, where it is pointed, to the heel, where it is open.

The handle portion 7 of the iron comprises pieces 8 and 9. Piece 8 consists of a member 10 with beveled edges 11 of same inclination as undercut sides 6 of groove 5, the same being of dovetailed form and the construction being such that piece 8 will slide into and fit snugly in said groove and firmly hold the handle to the base. At the front end of piece 8 the bottom and side surfaces thereof are inclined upwardly and inwardly, respectively, at 12 and 13, so that piece 8 can be easily inserted in groove 5.

A catch 14 is provided to prevent piece 8 from sliding out of groove 5 except when desired. Catch 14 is partially seated beneath the top surface of piece 8 and in a recess 15 therein. The catch is upturned at its rear end 16, which projects up into and is pivoted at 17 in a dome 18, which is slightly raised above the surface of piece 8. Forward of dome 18 is another similar dome 19, wherein is seated a coiled spring 20, a part of which is disposed around a pin 21, projecting above catch 14, this spring having a tendency to force said catch down. Catch 14 also carries near its forward end a downwardly-projecting part 22, which is arranged to catch in a recess 23 in groove 5 to prevent piece 8 from sliding out of said groove, part 22 being caused to drop 100

in recess 23 by the weight of catch 14 and the action of spring 20.

The under surface of catch 14 inclines upwardly at 24 from part 22, this inclination being provided to enable part 22 to slide easily in groove 5 and over recess 23 and also for the purpose of affording means to prevent catch 14 dropping too far beneath piece 8, incline 24 being arranged to rest on a corresponding incline 25 in said piece to accomplish this. A lip 26 is also provided to prevent too great fall of catch 14, said lip resting on the surface of piece 8.

A finger-piece 27 projects above the forward end of catch 14 for digital operation, the catch being thereby raised at one end to permit the handle to slide out of groove 5, and thus release the same from the base of the iron.

A handle-piece 28 stands upward at the forward end of, and is preferably made integral with, piece 8, and at the top piece 28 is secured to piece 29, which curves rearwardly and downwardly to the rear part of piece 8,

where it is fastened, the handle or grip 7 being thus formed of two pieces and a strong 25 construction thereby attained.

Having thus described my invention, what I claim as new, and desire to secure by Letters Patent, is—

In combination with a sad-iron having a 30 longitudinal groove opening to a recess in the top thereof, a handle portion comprising a member arranged to slide within said groove and provided with a dome, and a horizontally-disposed catch provided with a shank having 35 an upwardly-offset portion, and means for pivotally securing said offset portion on the handle portion including a pin engaging the opposite walls of the dome.

In testimony whereof I affix my signature in 40 presence of two witnesses.

BELLE MUMBY.
